C. J. JANSKY.

CLOSURE FOR GRAVES.

APPLICATION FILED DEC. 21, 1920.

1,381,309.

Patented June 14, 1921.

Fig. 1.

Fig. a.

Fig. 3.

A technical drawing of a mechanical assembly. It features a horizontal scale with markings at 10, 20, 30, and 40. A circular component, labeled '5' at the top and '14' at the bottom, is positioned above the scale. A small rectangular label with the number '0' is located near the center of the scale. A vertical column of numbers '23', '1', '6', and '8' is positioned to the right of the scale. The drawing is oriented horizontally.

Charles J. Jansky

W. H. Wess
T. F. Britt

A technical drawing of a key, labeled 23, with a rectangular head and a notched profile. A line labeled 10 connects to the head, and a line labeled 30 connects to the profile. A line labeled 26 connects to the shank. To the right of the key, the word "By" is written above two signatures of the name "Young". Below the signatures, the word "P" is written above a stylized, decorative flourish.

UNITED STATES PATENT OFFICE.

CHARLES J. JANSKY, OF TWO RIVERS, WISCONSIN.

CLOSURE FOR GRAVES.

Specification of Letters Patent. Patented June 14, 1921.

Application filed December 21, 1920. Serial No. 432,257.

To all whom it may concern:

Be it known that I, CHARLES J. JANSKY, a citizen of the United States, and resident of Two Rivers, in the county of Manitowoc and State of Wisconsin, have invented certain new and useful Improvements in Closures for Graves; and I do hereby declare that the following is a full, clear, and exact description thereof.

10 My invention relates to a device for temporarily closing a grave while the mourners are arriving and keeping it thus closed until the mourners have departed, except for the brief moment while the coffin is being lowered.

15 It has hitherto been the practice to dig a grave and to leave it open after the coffin has been lowered and while the mourners are standing around the grave. This practice, especially in bad weather, produced an unfortunate and unnecessarily sad impression upon the mourners.

20 The object of my invention is to provide a device which may alleviate, to a considerable extent, the sorrow upon this occasion.

25 More specifically stated, the object is to provide a device which may act as a temporary closure to cover and protect the grave while the mourners are arriving and until it is time for the coffin to be lowered, and which may then be opened and immediately closed again as soon as the coffin has been lowered.

30 I will now describe my invention specifically and reference will be had to the accompanying drawings, in which—

35 Figure 1 is a plan view.

Fig. 2 is a horizontal sectional view.

Fig. 3 is a vertical section on the line 3—3 of Fig. 1, and

40 Fig. 4 is a vertical section on the line 4—4 of Fig. 3.

45 Like characters will refer to like parts throughout the several views. The device consists of four hollow corner blocks 5, 6, 7 and 8 connected by the longitudinal channel bars 9 and 10, and by the transverse members 11 and 11^a. Two shafts 12 and 13 are mounted longitudinally within the channel bars 10 and 9 respectively, the ends of said 50 shafts being journaled in the corner blocks, each of these shafts is oppositely threaded from its ends to the center for a purpose which will later appear. A shaft 14 is journaled at one end of the device in the blocks 5 and 6 and operatively connected with the 55 shafts 12 and 13 by the bevel gears 15 and

16 respectively. A shaft 17 is journaled at the other end of the device in the blocks 7 and 8. This shaft is provided with the reversing gears 18 and 19, which are splined on the shaft and operable by the lever 20, to cause either one of said gears to mesh with the gear 21 on the end of the shaft 13. Two blocks 22 and 23 are threaded on to the oppositely threaded ends of the shaft 13 and 60 two similar blocks 24 and 25 are threaded on to the shaft 12. The blocks 23 and 25 are connected by a rod 26, and the blocks 22 and 24 are connected by a rod 27. These two rods are secured to the ends of curtains 30 and 31 respectively, said curtains being 65 rolled upon the respective rollers 28 and 29 journaled on lugs projecting from the corner blocks. These rollers are held by the usual springs 32 and 33 so as to hold the curtains taut, no matter what the position of the rods 26 and 27 may be. The shaft 17 is connected with the spring motor 34, which may be wound by a key or the like 35. The 70 operation of my device is as follows:

75 When the coffin has been placed above the closure, which is then in the position shown in Fig. 1, the lever 20 is moved so as to place the proper one of the reversing gears in mesh with the gear 21. The oppositely threaded rods 12 and 13 are rotated and the curtains rapidly drawn back. The rotation of the shafts 12 and 13 will cease as soon as the threaded blocks come in contact with the corner blocks. The coffin is then lowered, 80 the gear reversed and the curtains are 85 quickly closed. It is to be understood that the gear reversed and the curtains are 90 quickly closed. It is to be understood that my invention is not limited to the precise structure shown and described, but includes all equivalents that fall within the scope of 95 the appended claims.

I claim:

1. A closure for graves comprising a frame through which the coffin may be lowered, a curtain mounted at each end of the frame, means for drawing the curtains together to form a closure and means for retracting the curtains to uncover the grave.

2. A closure for graves comprising a frame through which the coffin may be lowered, a curtain mounted at each end of the frame, a motor and means operatively connecting said motor to said curtains, said means including a reversing gear whereby said curtains may be moved into a position 105 to cover or uncover the grave.

3. A closure for graves comprising a

frame through which the coffin may be lowered, curtains mounted at each end of the frame, blocks secured to the ends of the curtains, screw threaded shafts on which said blocks are mounted, each of said shafts having its two halves oppositely threaded whereby when the shafts are rotated, the blocks will approach or recede from each other, ac-

cording to the direction of rotation and a reversing gear for driving said shafts in either direction at will.

In testimony that I claim the foregoing I have hereunto set my hand at Two Rivers, in the county of Manitowoc and State of Wisconsin.

CHARLES J. JANSKY.
